UNITED STATES PATENT OFFICE.

JOHN H. FUCHS, OF CHARTIERS, ALLEGHENY COUNTY, PENNSYLVANIA.

CARPET-STRIP OR DOOR-SILL.

SPECIFICATION forming part of Letters Patent No. 352,745, dated November 16, 1886.

Application filed March 6, 1886. Serial No. 194,311. (No model.)

To all whom it may concern:

Be it known that I, JOHN H. FUCHS, of Chartiers township, in the county of Allegheny and State of Pennsylvania, have invented a new and useful Improvement in Carpet-Strips or Door-Sills; and I do hereby declare the following to be a full, clear, and exact description thereof.

My invention relates to carpet-strips or sill-pieces for doors, these carpet-strips being generally placed on the top of the door-sill to provide for a close joint between the base of the door and the floor, while at the same time it permits the door to swing out above the carpet of the room, and forms an edge against which the carpet is placed.

My invention has reference to that class of door-sills or carpet-strips in which the central portion is adjustable vertically so as to coincide with the base of the door, so as to save labor in adjusting the door to the strip in hanging the door, or arrange a neat fit in case of sagging or warpage of the door or the wear or warpage of the sill, its object being to provide an adjustable sill or strip which will be yielding under the pressure of the door as it swings over it, so as to maintain a perfectly dust, water, or air tight joint with the base of the door, which can be adjusted perfectly to the base of the door in case of its shrinkage, warpage, or sagging, and in which the yielding and adjustable portion is held firmly in place in the door-sill.

The construction of the door sill or carpet-strip is hereinafter fully set forth and claimed.

To enable others skilled in the art to make and use my invention, I will describe the same more fully, referring to the accompanying drawings, in which—

Figure 1 is a perspective view, partly in section, showing my improved carpet-strip. Fig. 2 is a sectional perspective view showing the strip opened to permit the adjustment thereof; and Fig. 3 is a like view of the interposed cushion or strip.

Like letters of reference indicate like parts in each.

The door-sill or carpet-strip 1 is formed in two sections, 2 3, between which is an interposed strip or cushion, 4, this interposed cushion being generally arranged at about the cen-

ter of the carpet-strip, so that it is directly under the door 5 when closed.

One portion of the carpet-strip—such as the portion 3—is firmly and permanently nailed to the floor, while the other portion, 2, thereof is secured by screws or like removable devices, and the inner faces, 6, of these two parts of the carpet-strip are preferably formed inwardly inclined toward the base thereof, so as to form a dovetailed space between the two parts of the carpet-strip, to hold the interposed cushion and prevent the same from being easily withdrawn from its position between the two parts 2 3 of the carpet-strip.

The interposed strip 4 is made of rubber, leather, or like flexible material which will form a yielding cushion when the door is closed over the same, thus acting to form a perfectly air-tight joint between the carpet-strip and the door. For ordinary purposes, however, the cushioning-strip 4 is formed of a block of rubber having a curved upper face, as shown, this rubber block being held in the dovetailed space between the faces 6 of the two portions of the carpet strip, and so forming a yielding cushion between the same, and interposing little or no resistance to the foot in walking over the carpet-strip.

The cushion 4 may either rest upon or be secured to the under strip, 7, it being generally preferred that this cushion be secured to the under strip by gluing, screwing, or in other suitable manner, and this under strip, 7, acts to support the cushion in its proper position and provide means for adjusting the cushion properly to the base of the door, as in case the door fits close down upon the body of the carpet-strip and too much friction is created between the door and the cushion the cushion can be lowered by simply planing off the under face of the strip 7, and if the base of the door is of peculiar shape—such as concave or convex—the cushion can be perfectly adjusted thereto, either by conforming the under strip, 7, to the base of the door, or by the employment of blocks or chips 8, of wood or other suitable material, under the supporting-strip 7. In like case, where there is a large space between the door and the carpet-strip, the entire strip 7 and the interposed cushion 4, resting thereon, may be supported on these chips or

blocks in such manner as to adjust the cushion perfectly to the base of the door, and as soon as an adjustment of the strip thereto is obtained the movable portion 2 of the carpet-strip is forced against the interposed strip or cushion 4 and secured to the floor or door-sill in such position as to firmly hold the interposed cushion or strip in place, this being generally done by means of screws, as shown. 5
In case either the base of the door or the interposed strip should wear in such manner as to leave a space between them, it is evident that the strip can be easily adjusted so as to take up or close any such space. 10
By my improved carpet-strip I am enabled to entirely close the space between the door and floor, and prevent the entrance of air or water under the door when closed, and at the same time I overcome much of the labor of 15 the carpenter in hanging doors, as the carpet-strip can be adjusted to the door instead of the door to the carpet-strip. 20
The device is simple in construction, and can be employed to advantage with any form 25 of door, and at the same time, as the inter-

posed piece or cushion extends but slightly above the body of the carpet-strip, it presents substantially no obstruction in walking over the carpet-strip.

What I claim as my invention, and desire 30 to secure by Letters Patent, is—

1. The combination, with the longitudinally-divided door-sill or carpet-strip, of the interposed rubber or like yielding strip 4, the rigid supporting strip 7 under the same, and means 35 for adjusting said interposed strips vertically, substantially as and for the purposes set forth.

2. The combination, with the longitudinally-divided carpet-strip, of the interposed rubber or like yielding strip 4, the rigid supporting- 40 strip 7, secured thereto, and means for adjusting said interposed strips vertically, substantially as and for the purposes set forth.

In testimony whereof I, the said JOHN H. FUCHS, have hereunto set my hand.

JOHN H. FUCHS.
